BOOKBINDER CASING AND METHOD OF
MAKING SAMEFrank Stanley Schade, Holyoke, Mass., assignor
to National Blank Book Company, Holyoke,
Mass., a corporation of Massachusetts

Application May 5, 1937, Serial No. 140,783

5 Claims. (Cl. 281—31)

This invention relates to an improvement in casings for loose leaf binders and method of forming the casings with pockets.

In the best form of the invention that I have conceived for practical use, the casing is made according to my prior Patent 2,051,908 of August 25, 1936, and the improvement consists in forming pockets in the casings simultaneously with the formation of the casing and without any substantially increased cost beyond the mere cost of a small amount of additional material for the pocket construction. That is to say, the same economical method of making a good casing may be used under this invention to include the pocket making operation without increasing the machine or labor cost of the casing. There is of course the added and small cost of additional material for the pocket, but this alone is so small that I can make the casings with 20 pockets at almost the same cost as the casings before my invention were made without pockets. There is not enough difference in cost to cause any necessary increase in price to the purchaser.

The invention is disclosed by the accompanying drawings and following description.

Fig. 1 is a plan view of a casing in flat form, made according to the invention, parts being broken away to show the inner construction;

Fig. 2 is an end view of the casing skeleton 30 with pocket parts;

Fig. 3 is a fragmentary perspective view on a larger scale, with parts broken away, showing the skeleton assembled;

Fig. 4 is a plan view, with parts broken away, 35 showing the completed skeleton; and

Fig. 5 is a diagrammatic view showing the preferred manner of carrying out the method.

In the drawings, the scale of the parts has been exaggerated, particularly as to the thickness, to make the construction clear.

Comparison with the disclosure of my aforesaid Patent 2,051,908 will show that the disclosure made herein is the same with the exception of the insertion of pocket strips of material and 45 the making of the finished casing with instead of without pockets. I will also mention one or two useful modifications wherein the pocket making problem is solved with variations.

Referring to Figs. 2-4, the construction of the 50 binder casing starts with two plies of thin cardboard 10 and 11, which both have the overall dimensions of the binder to be built. The ply 10 which will lie inside the completed binder and will be referred to as the inner ply is per- 55 forated, scored, or otherwise weakened along two

sets of parallel lines 12—12' and 13—13'. The perforation lines 12' and 13' lie along the edges of the back panel portion 14 of the binder case, and the lines 12 and 13 define the inner edges of the side panels 15 and 16. Those portions 22 5 of the inner ply 10 which lie between each set of adjacent perforation lines 12—12' and 13—13' are used to provide a hinge zone in the completed binder in a manner which will be later described.

In the back panel portion 14 between the plies 10 and 11 I insert a stay or strip 17 of thin metal extending from the top to the bottom of the binder case and slightly less in width than the back panel portion. This stay 17 has rivet holes 18 provided in it to allow for subsequent attachment of the ring mechanism. To fasten the stay, I cement it to both plies of the back panel portion 14, carrying the cement to perforation lines 12' and 13' so that the stay is completely incorporated in the back panel portion. 20

Adjacent the perforation lines 12 and 13 and between the plies 10 and 11 I insert a set of stays 19, slightly narrower than 17 but likewise extending from the top to the bottom of the casing. However, in this case I cement the strips 19 to 25 the outer ply 11 only and do not cement the side panel portions 15 and 16 of the separate plies together (see Fig. 2). These strips 19 serve to reinforce the side panel members against the thrust of the ring mechanism when the completed binder is in closed position. 30

As a final operation before the skeleton of the binder is ready for the case making machine, I provide for a pocket in the side panel 15 of the inner ply 10. To do this I cement a cardboard 35 strip 20 along the outer edge of the panel 15, the cement being applied along the short edge 21 of the inner ply 10 only. This leaves the cardboard strip attached like a flap to the outer edge of the side panel 15. As this flap provides the 40 pocket in the binder, ink, paint, or other coloring material is applied to the surface of the inner ply 10 from the point where the flap is attached to a slight distance beyond the open end of the flap. Thus, the completed pocket will have a 45 lining matching the rest of the binder cover paper.

The skeleton is placed as a unit in a case making machine which pastes a suitable cover sheet 23 to the outer face of ply 11, then folds the edge 50 portions 24 around the edges of the plies 10 and 11 and three edges of the cardboard flap 20 (see Fig. 4), and pastes the folded edges down.

The cardboard flap 20 has now been attached to the ply 10 along the outer edge of panel 15 55

and is closed along its two shorter edges by the edge portions 24 of the cover sheet 23. In this manner I have provided a pocket with its opening 25 towards the back panel portion 14 of the binder case.

5 This is the preferred form to obtain the utmost in economy of pocket construction. However, if a sturdier construction is desired at slightly higher cost per unit, I cement a stay of 10 kraft paper along the short edges of the pocket before the cover sheet 23 is applied. This insures that the pocket will not tear loose along the turned edges 24 of the cover paper.

15 The portions 22 of the inner ply 10 lying between the perforation lines 12-12' and 13-13' are now removed, the ends being slipped out from under the edges 24 of the cover sheet 23. The side panel portions 15 and 16 of inner ply 10 are now held in position only by the edges 24 of 20 the cover sheet and may slip slightly relative to the corresponding panels of ply 11.

25 The portions of ply 11 uncovered by removal of strips 22 serve as hinge lines or zones to allow the side panels 15 and 16 to be opened or closed as the book is used, the relative motion of the side panel pieces 15 and 16 of each ply 10 and 11 serving to facilitate this motion.

30 A single lining sheet 30 is pasted over the back panel portion and the side panels of ply 10, including the pocket of panel 15. The opening 25 of the pocket is then freed by slitting the liner sheet. The back panel portion 14 may then be pressed to a curved shape or left flat and the ring mechanism 35 installed to complete the ring binder shown in Fig. 1.

35 The particular construction used in applying the liner sheet and ring mechanism can of course be varied to provide a ring binder of higher quality. For instance, a liner sheet may be applied from the free edge of panel 16 to the opening 25 of the pocket. A separate liner may then be pasted to the pocket extending from the outer edge of panel 15 with a portion of the liner sheet turned under the pocket edge 25 to present a 45 neater appearance.

40 In a still more expensive type I can use a separate lining sheet of heavy paper or fabric for the back panel portion 14, making it wide enough to just overlap the hinge zone on each panel. 50 Then suitable lining sheets may be applied to each side panel. This construction is in many ways most desirable where the binder suffers rough usage as the hinge line of the side panels is materially strengthened.

55 Of course many variations of methods of applying the lining sheets will occur to those skilled in the art and I in no way limit myself to the particular arrangement described.

60 I carry out my construction method with cardboard plies and reenforcing strips in web form, as shown diagrammatically in Fig. 5. In that figure, cardboard plies 10 and 11 and flap 20 are fed from supply rolls not shown between presser rolls 40 and 41. The perforation lines 65 12-12' and 13-13' are made by a suitable wheel 42' before the ply 10 passes through the rolls. Similarly cement is applied to the web 20 by roll 42, roll 43 being merely a supporting roll for that portion of the web 20 to which adhesive is not applied. The metal strips 17 and 19 are fed in proper spaced relation through the presser rolls 70 40 and 41 from suitable supply reels, as indicated. Adhesive is applied to both sides of strip 17 and the under side only of strips 19 by the rolls 44. 75 Thus, strip 17 adheres to both plies 10 and 11,

while strips 19 adhere to ply 11 only. Punches 46 make the rivet holes 18 in strip 17 before the latter enters the rolls 40 and 41, and a suitable cutting tool 47 cuts off the webs into units having the structure of Fig. 2.

5 As will be appreciated from the above description and drawings, by my invention I have provided for an improved ring binder which can be manufactured in quantities at low cost but which has the more desirable features not found in this 10 class of product in the cheaper quality binders. The incorporation of a pocket in the side panel of a binder has always been desirable, but special operations have heretofore been necessary, which so increased the cost per unit as to make this 15 feature unavailable in all but the expensive ring binders. What I want to particularly emphasize is that by using the method outlined above it is possible to incorporate the pocket in the binder and keep the additional cost down to little more 20 than the cost of the pocket material itself.

What I claim is:

1. The method of making loose leaf binders which consists in simultaneously feeding strips of cardboard of indefinite length from rolls, at 25 least one of said strips having a width equal to the overall width of the binders to be built and at least one of which has a width equal to the width of a pocket to be built on the inside face of one of the binder cover portions, the outer edge of the latter strip being fed in alignment with an outer edge of the cover portion and with the strip contacting the inside face of such portion, and also simultaneously feeding from a roll a narrow strip of stiffening material in line 30 with the cardboard back panel portion of the binders to be built, progressively fastening the outer edge portions of the cardboard strips and the strip of stiffening material to the back panel portion by passing the same through pressure 35 rollers, progressively cutting off said laminated and fastened strips in lengths equal to the height of the binders to be built, and then laying on the outside face of each cut-off skeleton binder a layer of cover material with edges extending 40 beyond the overall dimension of the skeleton so as to turn over all around on the inside margin of the skeleton, turning over and fastening such edge portions around the overall dimensions of the binder skeleton and finishing the binder by 45 laying on usual lining strips on the inside face but without permanently closing the open end of the then formed pocket.

2. The method of making loose leaf binders composed of plies of cardboard having the overall flat dimensions of the casing to be built which comprises securing said plies together over those 50 portions only of the plies which are to become the back panel of the casing, cementing a narrow cardboard ply with one long edge along one short edge of the inner ply, applying a cover sheet to the exposed face of the outer ply, said sheet being of greater overall dimensions than the casing, turning over and cementing the edge portions of the cover sheet to the exposed face of the inner 55 ply and along three edges of the narrow ply, removing a narrow strip of the inner ply adjacent each side of the back panel portion of the inner ply, applying a single lining sheet covering the inner ply and exposed edge of the narrow 60 cardboard strip, and then slitting the lining sheet along the uncemented long edge of the narrow 65 cardboard strip to form a pocket.

3. The method of making loose leaf binders composed of plies of cardboard having the over- 70 75

all flat dimensions of the casing to be built, which comprises securing said plies together over those portions only of the plies which are to become the back panel of the casing, cementing a narrow 5 cardboard ply with one long edge along one short outer edge of the inner ply, applying a cover sheet to the exposed face of the outer ply, said sheet being of greater over all dimensions than the casing, turning over and cementing the edge portions of 10 the cover sheet to the exposed face of the inner ply and along three edges of the narrow ply, removing a narrow strip of the inner ply adjacent each side of the back panel portion of the inner 15 ply to form a hinge zone, applying a heavy lining sheet to the back panel portion of the inner ply, said heavy lining sheet extending beyond the removed portion of the inner ply, and then applying separate lining sheets to those portions of the inner ply separated from the back panel portion 20 thereof without covering the exposed edge of the narrow cardboard strip cemented to the inner ply.

4. The method of making loose leaf binders which consists in simultaneously feeding strips or 25 webs of cardboard of indefinite length from rolls, with the strips in alignment along one edge, the width of at least two of the webs being equal to the overall width of the binder, and at least one of which has a width equal to the width of a 30 pocket to be built on the inside face of one of the binder cover portions, perforating one of said wider webs in a manner to permit subsequent removal of a portion thereof along narrow zones defining the long edges of the back panel portion 35 of the binder, inserting continuously between the wider webs thin strips of stiffening material in those portions of the webs which are to become the back and side panels of the casing, cementing both webs to the stiffener in the back panel 40 portion, cementing the stiffeners in the side panel portions to one of the two webs only to form a composite web, cementing said narrower web to the wider web along the aligned edge, trans-

versely severing from said web a length substantially equal to the desired overall length of the casing, applying a cover sheet to the outside face of each severed length with the edges of the cover sheet extending beyond the overall dimensions of the severed length, folding the edge portions of the cover sheet around the exposed edges of the severed webs, and cementing said edge portions to the exposed face of the webs, removing the portion of the wide perforated web lying between 10 said perforations and applying the usual lining strips without closing the open end of the pocket formed by the severed length of narrow web. 5

5. In a loose leaf binder, a casing structure 15 composing outer back and side panel members formed as an integral sheet, a thin reenforcing strip secured to the inner face of the back panel portion of said sheet, an inner back panel member secured to the reenforcing strip to enclose said strip between the back panel members, inner side 20 panel members having their respective top, bottom, and outer side edges coinciding with the corresponding edges of the side panel portions of said sheet, the inner side edges of said inner side panels being spaced from the side edges of the 25 inner back panel member to form a hinge zone, stiffening strips positioned between the side panel members adjacent said hinge zones, said stiffeners being cemented to only one of the side panel members between which they are positioned, a sheet 30 of pocket material extending from the top to the bottom of the casing structure along the edge of one inner side panel portion, said pocket sheet being narrower than the side panel portion with its outer long edge cemented to the outer edge 35 of the side panel portion, a cover sheet having its edge portions folded over and secured to the inner side panel members and pocket member to hold the side panel members in position and close the short edges of the pocket, and a lining sheet 40 extending across the inner face of the binder casing but not closing the open edge of the pocket. 40

FRANK STANLEY SCHADE.
